UNITED STATES PATENT OFFICE.

FAY O. FARWELL, OF DUBUQUE, IOWA, ASSIGNOR OF ONE-HALF TO THE ADAMS COMPANY, OF SAME PLACE.

DESIGN FOR A HOT-AIR REGISTER.

SPECIFICATION forming part of Design No. 27,269, dated June 29, 1897.

Application filed February 1, 1897. Serial No. 621,572. Term of patent 14 years.

To all whom it may concern:

Be it known that I, FAY O. FARWELL, a citizen of the United States, residing at Dubuque, in the county of Dubuque and State of Iowa, have invented a certain new and original Design for Hot-Air Registers; and I do hereby declare the following to be a full, clear, and close description thereof.

My invention has relation to new and original designs for "hot-air registers," with reference to those secured to the ceiling and through which the stovepipe passes; and it essentially consists in a decorated circular register-plate secured to the ceiling overhead, through which the stovepipe passes, and a decorated plate which when the pipe is removed is placed over the opening formerly occupied by the pipe, all of which will be fully described in the following specification and illustrated in the accompanying drawings, in which—

Figure 1 is a plan view of the register-plate with a pipe removed. Fig. 2 is the register-plate with the decorated plate set in its opening when the pipe is removed.

Like letters of reference denote corresponding parts in both drawings.

The register-plate Y is designed with an

outer circular plate F, which is decorated with some ornamental work, like scrolls. The central opening G is immediately surrounded by a flange h. The plate F and flange h are connected together by ornamental open-work K.

The design of the central plate L (shown in Fig. 2) consists of a decorated centerpiece M, with a number of leaves projecting from the periphery of said piece M and engaging with the flange h. When the pipe is removed, this plate L (shown in Fig. 2) is placed over the opening in the register and engages with the flange h and covers the opening formerly occupied by the stovepipe, making a decorative covering for the pipe-hole.

Having now described my design, what I claim is—

The design for hot-air-register plates as herein described and illustrated in the drawings.

In testimony whereof I affix my signature in presence of two witnesses.

FAY O. FARWELL.
